(57) **CLAIM**

The ornamental design for a kinetic sculpture, as shown and described.

DESCRIPTION

FIG. 1 is a perspective view of the invention;

FIG. 2 is a front view of the invention shown in FIG. 1;

FIG. 3 is a left side view of the invention shown in FIG. 1;

FIG. 4 is a right side view of the invention shown in FIG. 1;

FIG. 5 is a rear view of the invention shown in FIG. 1;

FIG. 6 is a top view of the invention shown in FIG. 1; and,

FIG. 7 is a bottom view of the invention shown in FIG. 1.

1 Claim, 4 Drawing Sheets**FIG. 1**

FIG. 3

FIG. 2

FIG. 6

FIG. 7
